(57) CLAIM

The ornamental design for a push button for a dispenser, as shown and described.

DESCRIPTION

FIG. 1 is a perspective view of a push button for a dispenser showing my new design;

FIG. 2 is a right elevation view thereof;

FIG. 3 is a left elevation view thereof;

FIG. 4 is a top plan view thereof;

FIG. 5 is a bottom plan view thereof;

FIG. 6 is a front elevation view thereof; and,

FIG. 7 is a rear elevation view thereof.

The broken line showing of the interior of the push button is for illustrative purposes only and forms no part of the claimed design.
